REGULATOR SYSTEM

James P. Houck, Wilkinsburg, Pa., assignor to
 Westinghouse Electric & Manufacturing Company, East Pittsburgh, Pa., a corporation of Pennsylvania

Application April 5, 1941, Serial No. 387,046

8 Claims. (Cl. 13—12)

My invention relates to a furnace regulator system and more particularly to means for adjusting the setting of the regulator upon changes in the operating conditions of the circuit supplying energy to the furnace.

In the operation of electric arc furnaces of the movable electrode type, it is customary to provide a motor-operated mechanism for each electrode for raising and lowering the electrode as controlled by a regulator that is automatically responsive both to the value of current flowing in the electrode circuit and also to the voltage conditions in the electrode circuit. Such operation is desirable in order to obtain constant electrode arcs and even heating effects by the various electrodes connected to the several conductors of an alternating-current polyphase circuit supplying the furnace.

In the operation of melting furnaces, it is necessary to operate the furnace at a relatively high voltage during the early stages and, as the melting down process proceeds and the resistance of the material in the furnace decreases, to lower the applied voltage. This may be done by changing the tap connections of the transformer supplying power to the furnace. When this is done, the voltage applied to each electrode of the regulator changes, and it becomes necessary to change the setting of the voltage coil of the regulator in order to maintain a balanced pull between the voltage and current coils for the new voltage condition of the supply circuit.

In accordance with the present invention, means are provided for effecting a change in the supply voltage to the furnace, and a simultaneous change in the setting of the regulator automatically upon operation of the same control means. This eliminates many of the parts formerly employed in systems of this character, in which a plurality of separate relays were provided for changing the adjustment of the regulator under manual control, and also avoids the necessity of making these adjustments separate from the operation of the tap-changing mechanism for the transformer supplying power to the furnace. The control circuits are further simplified in that it is possible to make use of a motor-operated mechanism which operates through a sequence of tap-changing steps always in the same direction, thus eliminating the formerly used reversing type motor and the more complicated control required to effect the desired tap change in the use of systems operated by such reversing motor.

The system in accordance with the present in-

vention is still further simplified from an operating standpoint in that the master control switch is operated to a single position only, depending upon the desired change in both the tap-changing mechanism and the voltage adjusting mechanism, thus avoiding the necessity of a series of operations when the tap-changing mechanism is to be operated through several tap-changing steps.

10 It is an object of my invention to provide a furnace regulator system of the above-indicated character in which means is provided for automatically changing the setting of the regulator upon a change in the voltage of the supply circuit for supplying power to the furnace.

More specifically, it is an object of the invention to provide means for varying the adjusting resistors of the voltage coil of a furnace regulator of the movable electrode type simultaneously with the operation of the tap-changing mechanism associated with the transformer supplying power to the furnace.

Further objects and advantages of the invention will be apparent from the following description of a preferred embodiment, reference being made to the accompanying drawing, in which the single figure illustrates the circuits and apparatus employed in said embodiment.

Referring to the drawing, an arc furnace structure is illustrated at 1 having a conducting casting shown grounded at 2 and adapted to contain a bath of metal or similar material 3 to be heated. The furnace is likewise provided with three movable electrodes 4, 5 and 6 connected by conductors 7, 8 and 9, respectively, to the secondary winding 12 of a transformer bank having primary windings 13 shown connected in delta and supplied from circuit conductors 14, 15 and 16 from a three-phase, alternating-current source 40 as controlled by a circuit breaker 17.

45 Furnace regulating equipment is provided for each of the three electrodes 4, 5 and 6, the equipment for operating electrode 4 only being illustrated for the sake of simplicity, and comprising a cable 18 for raising and lowering the electrode which passes over a pulley 19 above the electrode, and a reel 22 that is operated by a motor 23 having field windings 24 and 25 upon the flow of current from a source 26 as controlled by a regulator 21.

The regulator 21 comprises a movable beam 28 mounted on a pivot 29 and normally held in its mid or balanced position by spring members 31 and 32. Two electromagnets are provided connected to the lever 28 at opposite ends thereof,

one comprising a current coil 33 connected by conductors 34 and 35 to a current transformer 36 to be energized in accordance with the current flowing in the conductor 7 to the electrode 4. The other electromagnet is provided with a voltage coil 37, one side of which is connected by conductor 38 to the furnace casing 1, and the other side of which is connected through conductor 39 and selected resistor elements 41, 42, 43 and 44 to conductor 7 in accordance with the voltage existing between the electrode 4 and the furnace casing.

A tap-changing mechanism is provided for changing the tap connections of the primary winding 13 of the transformer, shown as including a movable contact member 45 for the mechanism associated with each phase of the transformer and a plurality of fixed contact members 46, 47, 48 and 49 corresponding to four tap positions. The tap-changing mechanism is operated by a suitable mechanical means which is herein illustrated as a simple shaft 52 that is controlled by a motor 53 having an armature winding 54 and a field winding 55 that are supplied with direct-current energy from supply conductors 56 and 57. The shaft 52 also operates a cam 58 for controlling cam switches 61, 62, 63 and 64 corresponding to the four tap positions of the tap-changing mechanism and which serve as limit switches for interrupting the operation of the tap-changing mechanism as it reaches a selected tap position. The apparatus is controlled by a master switch 65 having an operating handle 66 and a shaft 67 for actuating the three contact members 68, 69 and 70 to any one of four operating positions indicated by the four slots 71, 72, 73 and 74 in a locking mechanism into which the arm 75 is adapted to be positioned. A spring member 76 is provided, one end of which engages a fixed abutment 77, which also serves as a guide for the shaft 67, and a movable abutment 78 attached to the shaft 67 for biasing it toward the left, as viewed in the drawing, to effect pressure between the several contact members 68, 69 and 70 with their cooperating contact members.

The circuit breaker 17 is provided with an opening magnet having a winding 81 through which a circuit may be completed from a battery 82 upon operation of a pushbutton switch 83 to a circuit closing position and a magnet having a closing winding 84 that may be energized from the battery 82 upon closure of the pushbutton switch 85. The magnets having windings 81 and 84 operate the circuit breaker to its circuit-closing position in a well-known manner, and likewise operate interlock contact members 86 and 87 to their circuit-closing positions upon the opening of the circuit breaker 17 to connect the supply conductors 56 and 57, respectively, with circuit conductors 88 and 89 for a purpose to be later explained.

If the tap-changing mechanism is in its illustrated or first position, the entire primary windings of the transformer are connected between the circuit conductors 14, 15 and 16, thus impressing a minimum voltage per turn on the primary windings and also on the secondary windings to supply a minimum voltage to the electrodes of the arc furnace. In this position of the tap-changing mechanism, it will be noted that the contact member 68 of the master control switch 65 is in its first position in engagement with the fixed contact member 91 closing

10 a circuit from conductor 7 through conductor 92, contact members 68 and 91 and conductor 93 to shunt the several voltage adjusting resistors 41, 42, 43 and 44 from the voltage coil 37 of the regulator 27. When voltage is now applied to the furnace, a voltage will appear on the winding 37 forcing the associated magnet core upwardly to cause engagement between contact members 94 and 95 to close a circuit from the battery 26 through conductors 96 and 97, the field winding 24 and the armature winding of the motor 23 to effect operation of the motor in a direction to move the electrode downwardly. As the electrode is moved downwardly and engages the material 3 in the furnace, current will start flowing through the electrode 4 and the material to be melted, which material, upon the initial engagement of the electrodes therewith may have a relatively high resistance, thus permitting only a relatively small current flow. As the heating increases and the current through the electrode increases, the current in the current coil 33 of the regulator correspondingly increases and creates a force acting against the force of the voltage coil 37 until the current has increased to such a value that the magnetic pulls from the two coils 33 and 37 balance each other, and the contact member 94 again assumes its mid or illustrated position to interrupt the operation of the electrode motor 23. It will be noted that the three electrodes 4, 5 and 6 are connected in delta through the secondary winding 12 of the transformer supplying energy to the furnace, and that, as current flows through any one of the electrodes it must flow through at least one other of the three electrodes. The regulators for each of the three electrodes will so operate the electrodes that each electrode will ultimately carry the same current as the others.

As the current through the electrode increases above the value corresponding to a balance between the pulls exerted by the current coil 33 and the voltage coil 37, the contact member 94 will be moved downwardly into engagement with the contact member 98, closing a circuit from the battery 26 through conductor 99, motor field winding 25 and the motor armature to operate the motor 23 in a direction to raise the electrode 4 and decrease the current flow therethrough until the pull on the windings 33 and 37 again balance, thus effecting separation of the contact members 94 and 98 to interrupt the operation of the motor 23.

When it is desired to change the value of voltage applied to the secondary circuit conductors 7, 8 and 9, the tap-changing mechanism is operated in the following manner. The circuit breaker pushbutton switch 85 is first pressed to energize the opening coil 84 and cause operation of the circuit breaker 17 to its current-interrupting position and at the same time closing the interlock switches 86 and 87, which is a necessary step before the tap-changing mechanism will operate. If it is desired to operate the mechanism from the first tap position, as illustrated, to the second tap position, the switch shaft 67 is moved in the abutments 77 and 80 toward the right until the arm 75 is disengaged from the slot 71 and, at the same time, the contact member 69 is disengaged from the contact member 101 for a purpose to be later explained. The switch shaft 67 is then rotated toward the left until the arm 75 is in position opposite the slot 72 and slides into the slot 72 as the pressure on

the handle 66 released and the spring 76 forces the shaft 67 again toward the left, causing engagement of the switch contact members 68, 69 and 70, respectively, with cooperating contact members 102, 101 and 103. The switch contact member 68 closes a circuit from the conductor 7 through conductor 92, switch contact members 68 and 102 and conductor 104 in shunt to the resistors 42, 43 and 44, thus introducing the resistor 41 in circuit with the voltage coil 37 of the regulator. The purpose of this adjustment is to supply to the voltage coil 37 substantially the same voltage independently of the voltage supplied to the furnace electrode 4. The contact members 69 and 70 close a circuit from the supply conductor 56 through interlock switch 86, conductor 88, switch contact members 101 and 69, conductor 105, relay coil 106, conductor 107, limit switch 62, conductor 108, contact members 103 and 70, conductor 89, interlock switch 87 to supply conductor 57, thus causing the relay switch 109 to close and complete a circuit through the armature winding 54 of the motor 53 to operate the motor to move the cam 58 from its illustrated position in a clockwise direction, thus moving the three tap-changing contact members 45 in each of the three phases from engagement with the fixed contact members 46 and into engagement with the contact members 47. As the tap-changing mechanism reaches this position, the cam 58 will operate the limit switch 62 to interrupt the above-traced circuit through the relay winding 106, thus opening the relay switch 109 and interrupting the motor.

After the desired tap change has been effected, the circuit breaker closing pushbutton switch 83 may be pressed to energize the closing coil 81 for actuating the circuit breaker 17 to its circuit closing position, after which the regulating mechanism will continue to operate in the manner previously described.

If it is desired to select any other tap position of the mechanism, the master switch 65 may be operated to either its third or fourth position corresponding to the arm 75 being positioned in the slot 73 or 74, respectively, by first manually operating the handle 66 to slide the shaft 67 toward the right, as illustrated, and rotating it to the proper selected position, thereby permitting the arm 75 to enter the associated slot. This movement of the switch moves the contact member 68 to engage either the contact member 111 to close a circuit through conductor 112, or the contact member 113 to close a circuit through conductor 114 to shunt from the circuit of the voltage coil 37 of the regulator the number of the adjusting resistors 41, 42, 43 and 44 necessary to cause the application of substantially the same voltage to the coil 37 independently of the particular voltage applied to the furnace electrode. Similarly, the contact member 70 will be brought into engagement with the fixed contact member 115 or 116 to close a circuit either through conductor 117 and the limit switch 63 or conductor 118 and the limit switch 64 to perform the same function described above with respect to the limit switch 62.

The operation of the control switch 65 to any one of its four selected positions establishes a control circuit for the winding 106 of the relay 109 effecting the operation of the motor 53 in the same direction, and continuing that operation until the limit switch 61, 62, 63 or 64 corresponding to the position of the master switch 65 interrupts the motor circuit and stops the motor on the 75

selected position. The separation of the contact member 69 from the contact member 101 as the master switch 65 is moved from a selected number of its four positions to another position is for the purpose of preventing the relay winding 106 from becoming energized as the switch is moved from one selected position to another in cases where it is moved through more than a single step. In this manner, the operating circuit of

10 the tap-changing motor 53 is not completed until the switch is in its final position corresponding to the selected operation desired.

It will be appreciated that a regulator 27 and motor 23 and the control circuits therefor are 15 provided for each one of the electrodes 4, 5 and 6 and that the master control switch 65 will be provided with a contact 68 and the contact members and circuits associated therewith for each one of the three regulators, one only of which is 20 shown for the sake of simplicity.

It will be apparent to those skilled in the art 25 that modifications may be made in the circuits and apparatus illustrated and described, and I do not wish to be limited otherwise than by the scope of the appended claims.

I claim as my invention:

1. In a furnace-regulator system, the combination with a movable electrode and a motor for raising and lowering the electrode, of a regulator 30 for governing the operation of the motor to maintain a constant arc and having two electromagnets connected to exert opposing pulls, one of said electromagnets having a current coil responsive to the current flowing in said arc and the other of said electromagnets having a voltage coil responsive to the voltage of the arc, a transformer for supplying electric energy to said furnace electrode and having tap-changing mechanism for varying the voltage of said supply, and means 35 for operating the tap-changing mechanism and simultaneously adjusting the setting of the regulator.

2. In a furnace-regulator system, the combination with a movable electrode and a motor for raising and lowering the electrode, of a regulator 45 for governing the operation of the motor to maintain a constant arc and having two electromagnets connected to exert opposing pulls, one of said electromagnets having a current coil responsive to the current flowing in said arc and the other of said electromagnets having a voltage coil responsive to the voltage of the arc, a plurality of regulator adjusting resistor elements for varying the setting of the regulator, a transformer 50 for supplying electric energy to said furnace electrode provided with tap-changing mechanism, control means therefor including a switch for simultaneously selecting a predetermined operation of said motor and selection of said regulator adjusting resistors.

3. In a furnace-regulator system, the combination with a movable electrode and a motor for raising and lowering the electrode, of a regulator 65 for governing the operation of the motor to maintain a constant arc and having two opposing elements, one actuated by a current coil responsive to the current flowing in said arc and the other actuated by a voltage coil responsive to the voltage of the arc, a plurality of regulator adjusting resistor elements for varying the setting of the regulator, a transformer for supplying electric energy to said furnace electrode provided with tap-changing mechanism, control means for operating the tap-changing mechanism and for simultaneously varying the number of adjusting

resistor elements in series with the voltage coil of said regulator to maintain a substantially similar voltage range on said regulator voltage coil for the same arc voltage for any tap position of the mechanism.

4. In a furnace-regulator system, the combination with a movable electrode and a motor for raising and lowering the electrode, of a regulator for governing the operation of the motor to maintain a constant arc and having two actuating elements connected to exert opposing pulls, one of said elements having a current coil responsive to the current flowing in said arc and the other of said elements having a voltage coil responsive to the voltage of the arc, means in circuit with said voltage coil for adjusting the setting of said regulator, voltage adjusting means for supplying electric energy to said furnace electrode at any one of a plurality of voltage steps, motor operated mechanism operable in one direction only throughout a predetermined sequence of said steps for actuating said voltage adjusting means, a control means for controlling the operation of said mechanism to a selected one of said steps and for simultaneously adjusting the setting of said regulator.

5. In a furnace-regulator system, the combination with a movable electrode and a motor for raising and lowering the electrode, of a regulator for governing the operation of the motor to maintain a constant arc and having a current coil responsive to the current flowing in said arc and a voltage coil responsive to the voltage of the arc, a plurality of resistor elements associated with the voltage coil circuit for adjusting the setting of the regulator, voltage adjusting means for supplying electric energy to said furnace electrode at any one of a plurality of voltage steps, motor operated mechanism operable in one direction only throughout a predetermined sequence of said voltage steps for actuating said voltage adjusting means, control means including a limit switch associated with each step for stopping the motor operated mechanism on a selected step, and means for initiating the operation of the motor operated mechanism to a selected step and for simultaneously adjusting the resistor elements in series with the voltage coil of the regulator in accordance with the selected voltage step.

6. In a furnace-regulator system, the combination with a movable electrode and a motor for raising and lowering the electrode, of a regulator operative to maintain a balance between two opposing forces for governing the operation of the motor to maintain a desired arc, one of said forces being determined by a current coil responsive to the current flowing in said arc and the other of said forces being determined by a voltage coil responsive to the voltage across the arc, a plurality of regulator adjusting resistor elements for varying the setting of the regulator, a transformer for supplying electric energy to said furnace electrode provided with tap-changing mechanism, control means for controlling the operation of the tap-changing mechanism and for simultaneously varying the number of adjusting resistor elements in series with the voltage coil

of said regulator as the voltage applied to the said arc is varied, to reset the regulator for maintaining a balance between the pull exerted by the current coil and the pull exerted by the voltage coil for the new voltage supplied to the arc over a similar voltage range on said regulator voltage coil.

7. In a furnace-regulator system, the combination with a movable electrode and a motor for raising and lowering the electrode, of a regulator operative to maintain a balance between two opposing forces for governing the operation of the motor to maintain a desired arc, one of said forces being determined by a current coil responsive to the current flowing in said arc and the other of said forces being determined by a voltage coil responsive to the voltage across the arc, circuit adjusting means in circuit with said voltage coil for adjusting the setting of said regulator, voltage adjusting means for supplying electric energy to said furnace electrode at any one of a plurality of voltage steps, motor operated mechanism operable in one direction only throughout a predetermined sequence of said steps for actuating said voltage adjusting means, a control means for controlling the operation of said motor operated mechanism to a selected one of said steps and for simultaneously adjusting the setting of said circuit adjusting means for adjusting the arc voltage at which the pull exerted by the current coil will balance the pull exerted by the voltage coil proportionally to changes in the voltage applied across the arc.

8. In a furnace-regulator system, the combination with a movable electrode and a motor for raising and lowering the electrode, of a regulator operative to maintain a balance between two opposing forces for governing the operation of the motor to maintain a desired arc, and having one of said forces being determined by a current coil responsive to the current flowing in said arc and the other of said forces being determined by a voltage coil responsive to the voltage across the arc, a plurality of resistor elements associated with the voltage coil circuit for adjusting the setting of the regulator, voltage adjusting means for supplying electric energy to said furnace electrode at any one of a plurality of voltage steps, motor operated mechanism operable in one direction only throughout a predetermined sequence of said voltage steps for actuating said voltage adjusting means, control means including a limit switch associated with each step for stopping the motor operated mechanism on a selected step, and means for initiating the operation of the motor operated mechanism to a selected voltage step position and for simultaneously adjusting the resistor elements in series with the voltage coil of the regulator in accordance with the selected voltage step for maintaining a substantially constant balanced pull exerted by said current coil and said voltage coil over substantially similar current and voltage ranges for any voltage step position of the motor operated mechanism.

JAMES P. HOUCK.
